UNITED STATES PATENT OFFICE.

WILLIAM B. MURRAY, OF DANVILLE, ILLINOIS, ASSIGNOR TO THE MILLER TRAIN CONTROL CORPORATION, OF STAUNTON, VIRGINIA, A CORPORATION OF VIRGINIA.

TRAIN-STOPPING APPARATUS.

Application filed May 6, 1918. Serial No. 232,905.

To all whom it may concern:

Be it known that I, WILLIAM B. MURRAY, a citizen of the United States, residing at Danville, in the county of Vermilion and 5 State of Illinois, have invented certain new and useful Improvements in Train-Stopping Apparatus, of which the following is a specification.

My invention relates to train stopping means, and has particular reference to the apparatus which contacts with a ramp and is mechanically operated thereby.

The present application is, in part, a continuation of my copending application Serial 15 No. 40,751, filed January 19, 1915, now Patent No. 1,337,255; dated April 20, 1920.

An important object of the invention is to provide apparatus of the above mentioned character, which is of simplified construction, and dispenses with the employment of an unnecessarily large number of parts.

A further object of the invention is to provide means whereby the pressure which is to be released by the shoe being moved by 25 the ramp, normally serves to retain the shoe in the lowermost position, and yieldingly opposes its upward movement.

A further object of the invention is to provide means to exhaust pressure upon the 30 apparatus, to stop the train, if the shoe proper should work loose or become separated from the reciprocatory bar carrying the same.

Other objects and advantages of the invention will be apparent during the course 35 of the following description.

In the accompanying drawings forming a part of this specification and in which like numerals are employed to designate like 40 parts throughout the same,

Figure 1 is a side elevation of apparatus embodying my invention, parts being shown in central vertical section,

Figure 2 is a horizontal sectional view 45 taken on line 2-2 of Figure 1,

Figure 3 is a similar view taken on line 3-3 of Figure 1,

Figure 4 is a side elevation of the apparatus, parts being shown in section,

Figure 5 is a horizontal section taken on 50 line 5-5 of Figure 4,

Figure 6 is a central vertical sectional view through the shoe and associated elements,

Figure 7 is a sectional view taken on line 55 7-7 of Figure 6,

Figure 8 is an enlarged sectional view 60 through the pressure operated apparatus to actuate the train stopping means, parts in elevation,

Figure 9 is a bottom plan view of the shoe insert, and

Figure 10 is a partly diagrammatic view of a ramp and associated circuit.

In the drawings, wherein for the purpose 65 of illustration is shown a preferred embodiment of my invention, the numeral 10 designates a vertically arranged guide, as a whole, comprising a cylinder 11, which is preferably cast integral with a plate or foundation 70 12. The plate 12 is provided with slots 12', to receive bolts (not shown), to clamp the plate to the frame-work of the engine or the tender. The plate 12 is insulated from the frame-work of the engine by any suitable means. The upper end of the cylinder 11 is closed by means of a cap or head 13, having an air tight connection therewith, and secured thereto, by means of bolts 14 or the like. 75

The cylinder 11 is provided with a depending extension 15, having an opening or bore 16, provided with flat sides 17 and curved ends 18, as shown more clearly in Figure 2. The extension 15 has grooves 15', upon its flat sides, and an air port 17', upon one flat side. The port 17' has its lower end in communication with the atmosphere, while its upper end leads into the lower end of the cylinder 11, beneath the piston 21, as 90 clearly shown in Figure 7. Depending from the cylinder extension 15 are oppositely arranged guide-ways 19, having transversely curved faces 20, as clearly shown in Figure

3. The sides of the guide-ways 19 are flush with the flat sides or faces 24, as shown.

Mounted to reciprocate within the cylinder 11 is the piston or piston valve 21, having packing 22, for forming an air tight fit.

The piston is arranged upon the upper end of a vertically movable bar 23, which has flattened sides 24 and transversely curved edges 25, as clearly shown in Figures 2 and 3. This bar is adapted to move within the cylinder extension 15 and also between the guides 19. The bar 23 is provided at its upper end with a reduced extension 26, adapted to pass through an opening 27 in the piston 21. This reduced extension is externally screw-threaded for the reception of a nut 28 which engages a washer 29, in turn holding the packing 22 upon the piston 21, and the piston upon the upper end of the bar 23.

The bar 23 is provided with a longitudinally extending port 30, passing through the upper end of the extension 26 thereof, and discharging at its lower end into the upper end of a recess or chamber 31, formed in the bar 23. Arranged within the recess 31 is a valve seat 32, adapted to engage with an upwardly seating valve 33, having a stem 34. This stem is surrounded by a compressible coil spring 35, serving to hold the valve seated.

The spring 35 contacts with the upper side or face of a shoe 36, provided at or near one longitudinal edge with a vertical extension plate 37, preferably cast integral therewith. This extension plate is bolted or otherwise rigidly clamped to the lower end of the bar 23 by bolts 38 or the like. It might be stated at this point, that should the shoe 36 work loose so that it would descend perceptibly with respect to the bar 23, or become separated from the bar 23, the pressure within the chamber 31 would unseat the valve 33, thus allowing the pressure 45 to escape to the atmosphere.

As more clearly shown in Figures 6 and 7, the shoe 36 is provided with a depending longitudinal flange 39, having a tapered inner face 40. Arranged opposite the flange 39 is a detachable plate 41, having an inclined face 42 and adapted to coact with the flange 39. This plate is adapted to engage the opposite edge of the shoe 36 and is provided with an over-hanging flange 43. The flange 39 and plate 41 have openings 44, receiving bolts 45, having nuts 46. The flange 39 and plate 41 serve to receive therebetween a hard iron insert 47, which is clamped to the same. From the foregoing description, it is obvious that if the insert 47 should drop out or become displaced, without injury to the shoe 36, the valve 33 would not be opened. The insert 47 is provided upon its lower contacting face with a 65 diagonally arranged groove 48, preferably

rectangular in cross-section, providing a sharp cutting edge 49, which serves to effectively clean the ramp, to be described, also enabling foreign material which may accumulate upon the shoe, to be discharged off 70 of the same through the groove.

The numeral 50 designates a cylinder, having a port 51 discharging into the upper end thereof. Pressure is supplied into the port 51 through a pipe 52. Mounted to reciprocate within the cylinder is a piston 53, having a contracted port 54. The piston 53 is connected with a rod 55, which is connected with train stopping means 56. When the piston 53 descends, the train stopping means 56 is actuated and the engine or train stopped. Leading into the lower end of the cylinder 50 is an outlet port 57 discharging into a chamber 58. The chamber 58 is adapted to exhaust into the chamber 59, leading into a pipe 60, which leads into a chamber 61, preferably cast upon the cylinder 11, as more clearly shown in Figure 5. The chamber 61 has communication with the lower end of the cylinder 11, above the piston 21 by means of ports 62.

The numeral 63 designates a contracted port, disposed between the chamber 58 and chamber 59. The chamber 58 has communication with the chamber 59 through means of a main port 64, adapted to be covered and uncovered by an upwardly seating valve 65, carrying a downwardly seating valve 66, adapted when in the lowermost position to cover a port 67, supplying air to a whistle 68. The valve 65 is connected with a vertically movable rod 69 connected with the core 69' of a solenoid 70. The port 63 is not sufficiently large to permit of the exhaust of pressure from beneath the piston 53, in sufficient volume to cause the piston 53 to descend. The ports 63 are preferably about $\frac{3}{2}$ of an inch in diameter.

One end of the winding of the solenoid 70 is connected with a wire 71, which is connected with the plate 12, as shown at 72. The opposite end of the winding of the solenoid 70 is grounded to the frame-work of the engine or tender, as shown at 73.

The numeral 74 designates a source of current, having one pole thereof connected with a ramp 75, by means of a wire 76 having a switch 76^a, connected therein. This ramp is curved longitudinally in a vertical plane and is adapted to contact with the shoe 36, and elevate the same. The opposite pole of the source of current 74 is connected with a rail 76' of the track by means of a wire 77.

The operation of the apparatus is as follows:

When the shoe 36 travels in proximity to the ramp 75, and the ramp is electrically connected with the source of current 74, as would be the case if the block were clear, the shoe 130

36 contacts with the ramp 75, which thereby closes a circuit to energize the solenoid winding 70. In this closed circuit current flows from one pole of the source of current 74, 5 through wire 76, ramp 75, shoe 36, wire 71, solenoid winding 70, wire 73, the frame-work of the engine, rail 76', and back through the wire 77 to the opposite pole of the source of current 74. When the solenoid 70 is thus 10 energized the valve 64 is seated, thereby cutting off communication between the chambers 58 and 59. The shoe 36 and bar 23 are now moved upwardly by the ramp 75, and the piston valve 21 will be shifted above 15 the chamber 61 and series of apertures 62. As a result of this movement, the chamber 61 is placed into communication with the port 17', which leads to the atmosphere, whereby the pipe 60 is placed in communication 20 with the atmosphere. However, as the valve 65 is seated, pressure will not now exhaust from beneath the piston 53, sufficiently, to cause the piston to descend, to actuate the train stopping means 56.

25 Assuming that the ramp 75 is disconnected from its source of current, as when the block is at danger, when the bar 23 was elevated, by contact of the shoe with the ramp, as above stated, the piston valve 21 would be 30 elevated above the chamber 61, and this chamber placed in communication with the atmosphere through the port 17'. The valve 65 would now remain unseated, thereby allowing pressure to exhaust to the atmosphere 35 beneath the piston 53. The piston would now descend and actuate the train stopping means 56.

40 It is to be understood that the form of my invention herewith shown and described is to be taken as a preferred example of the same, and that various changes in the shape, size, and arrangement of parts may be resorted to without departing from the spirit of the invention or the scope of the sub- 45 joined claims.

Having thus described my invention, I claim:

1. In apparatus of the character described, an upstanding cylinder adapted to be secured 50 to a vehicle, an extension formed on the lower end of said cylinder and having a port therein communicating with the atmosphere and with the lower end of said cylinder, a piston mounted to reciprocate within 55 the cylinder, a bar connected with the piston and extending through said extension, means to move the bar, a conduit connected with the cylinder, and leading into the same at a point near the lower end, pressure operated 60 train stopping means connected with said conduit, and means to move said piston upwardly beyond said conduit to permit communication with the atmosphere through said port.

65 2. In apparatus of the character described,

a reciprocating bar provided with a longitudinal port, a valve carried by the lower end of the bar to normally close the port, a shoe secured to the lower end of the bar and serving to hold the valve seated, and an insert from the shoe separate from the valve.

3. In apparatus of the character described, a shoe provided upon one side with a depending flange, a coacting plate disposed in contact with the opposite side of the shoe, a metallic insert held between the flange and plate, and bolts passing through the shoe and serving to hold the plate in place.

4. In apparatus of the character described, 80 a cylinder adapted to be secured to a vehicle and provided near one end with a port having communication with the end of the cylinder and with the atmosphere, a piston mounted to reciprocate within the cylinder and adapted to normally assume a position adjacent one end thereof, a bar connected with the piston to move it, a shoe connected with the bar, means to move the shoe, an outlet conduit leading into the cylinder upon 90 the side of the piston remote from the port when the piston is in the extreme end position, pressure operated train stopping means connected with the conduit and means actuated by the loosening of the connections by 95 the said bar and said shoe for actuating said train stopping means, comprising a port extending through said bar and communicating with the end of the cylinder remote from said first named port, a valve within the 100 port to close the same end, a spring extending intermediate said valve and said shoe.

5. In apparatus of the character described, 105 a substantially vertical cylinder, a piston mounted to reciprocate therein and normally held in the lower-most position by pressure within the cylinder, means whereby pressure is exhausted from the cylinder upon the upward movement of the piston, a reciprocating bar connected with said piston and provided with a longitudinal port, 110 a valve carried by the lower end of the bar to normally close the port and a shoe secured to the lower end of the bar and serving to hold the valve seated.

6. In apparatus of the character described, 115 a bar provided with a port, a valve carried by the lower end of the bar to normally close the port, and a shoe secured to the lower end of the bar and serving to hold the valve seated.

7. In apparatus of the character described, 120 a bar provided with a port, a valve carried by the lower end of the bar to normally close the port, a shoe secured to the lower end of the bar, and a spring extending intermediate said shoe and said valve, and serving to hold the valve seated.

8. In apparatus of the character described, 125 a shoe provided upon one side with

a depending flange, a co-acting plate disposed in contact with the opposite side of the shoe, a metallic insert held between the flange and plate, bolts passing through the shoe and serving to hold the plate in place, and means for removing foreign matter from the surface of the insert.

9. In apparatus of the character described, a shoe provided upon one side with a depending flange, a co-acting plate dis-

posed in contact with the opposite side of the shoe, a metallic insert held between the flange and plate, said insert being provided with a groove in its outer face, and bolts passing through the shoe and serving to hold the plate in place.

In testimony whereof I affix my signature.

WILLIAM B. MURRAY.
